UNITED STATES PATENT OFFICE

ERNEST JOSEPH PERRY, OF BIRMINGHAM, ENGLAND

LOOM FOR WEAVING CARPETS AND LIKE FABRICS

Application filed May 11, 1929, Serial No. 362,195, and in Great Britain July 18, 1928.

This invention has reference to looms for weaving Axminster carpets and like tufted pile fabrics, and is an improvement in or modification of the invention set forth in the specification accompanying my prior Patent 5 No. 1,718,486 dated June 25, 1929.

My present invention is designed to provide an improved method and means of locking and rigidly holding the sectional tufting 10 yarn tube and spool carrier frames upon the foundation case or frame, with the object mainly of rendering the mounting of each individual sectional frame independent of that of the adjacent sectional frame or frames, 15 and with the further objects of reducing the cost of the sectional frames, and facilitating the necessary manipulation of the same.

According to the present invention the sectional tube and spool carrier frames are provided with bearing plates adapted for locating engagement with the foundation case or frame and are adapted to be rigidly secured in position by locking devices provided on the foundation case or frame. Said locking 25 device preferably comprises a spring-pressed tooth or detent which cooperates removably with a notch in the respective bearing plate so as to be adapted to press the latter into close engagement with the foundation case or 30 frame, the tooth or detent being provided integrally on a flexible spring blade secured to the foundation case or frame, and its locking action being controlled by a lever or the like through the medium of a slide and incline, or other intermediate mechanism, and said lever or the like being arranged if desired for simultaneous control of locking devices operating respectively at or towards opposite ends of the sectional frame.

40 In order that the invention may be clearly understood and readily carried into practice, reference may be had to the appended explanatory sheet of drawings, upon which:

Figure 1 is a rear elevation (partly broken away) of a tube and spool carrier frame having the present improvements applied.

Figure 2 is a plan of Figure 1.

Figure 3 is an end elevation showing the foundation case or frame and one of the sectional tube and spool carrier frames in dis-

assembled relation, the view being partly in section taken on the line 3—3 of Figure 2.

Figure 4 is a perspective view of a part of the foundation case or frame, showing details of the locking devices thereon.

Figure 5 is a plan view taken in section on the line 5—5 of Figure 1, and also showing details of the locking mechanism.

Figure 6 is a view corresponding to Figure 5 but showing one of the locking teeth 60 or detents withdrawn for release of its respective sectional tube and spool carrier frame.

In a convenient embodiment of the invention, the foundation case or frame *a* is preferably of plain angular cross-section, as described in my above mentioned patent provided with brackets *b* at opposite ends having springs *c* or other means for detachably holding the frame in the endless carrier 70 chains. Openings or slots *d* are provided at longitudinally spaced intervals in one web of the foundation frame *a* to permit of sectional tube and spool carrier frames *e* being hung or attached in sufficient number to make the full 75 width required, two such sectional frames *e* being illustrated. Each sectional tube and spool carrier frame *e* is provided with substantially flat end plates *f* having terminal projections *g* with wedge-shaped extremities 80 and having hook projections *h* at one edge, the terminal projections *g* being adapted to pass through the aforesaid openings *d* in the one web of the angular foundation frame *a*, and the hook projections *h* being engageable 85 slidably over the edge of the other web of the angular foundation frame *a*, correct location of the sectional frames *e* being ensured by means of small fixed spacing plates *i* upstanding inwardly from the foundation 90 frame, in conjunction with coengaging pairs of spacing studs *j* projecting slightly from the outer faces of the end plates *f*. Each end plate *f* is also fitted on its inner face with an apertured spring blade *k*, the spools *l* being 95 removably mounted between opposite pairs of these spring blades. The multiplicity of tubes carried by the sectional frames *e* are indicated at *m*.

The sectional tube and spool carrier frames 100

e, as thus assembled and located in relation to the angular foundation frame *a*, are adapted to be independently secured in position by locking means provided on the foundation frame *a*. For this purpose a second series of openings *n* is provided in pairs in the other web of the foundation frame *a*, at longitudinally spaced intervals corresponding to the spacing of the first-mentioned series of openings *d* and of the end plates *f*, and within each of these second series of openings *n* is located a spring-pressed sliding tooth or detent *o* which is adapted to engage with a notch *p* provided on the edge of the end plate *f*, at a point adjacent the hook projection *h* thereon. This sliding tooth or detent *o* is inturned integrally at right angles from the free outer extremity of a flexible spring blade *q* of substantial strength, this spring blade *q* being secured longitudinally to the outer face of the respective web of the foundation frame *a* by means of a screw stud *r* or the like passed through the opposite extremity of the blade, the arrangement being such that the sliding tooth or detent *o* is normally pressed inwardly, under the action of its flexible mounting blade *q*, into tight engagement with the end plate *f* of the sectional frame *e*, the terminal projection *g* of the end plate being thereby 30 pressed into close locking engagement with the side of its respective opening *d* in the one web of the foundation frame *a*, and the hook projection *h* of the end plate being likewise pressed into close locking engagement 35 with the edge of the other web of the foundation frame.

The locking action of this spring blade *q* is controlled, for release of the sectional frame *e*, from a pivoted hand lever *s* also 40 mounted on the outer face of the foundation frame *a*, this lever *s* having a connecting rod *t* which extends longitudinally of the foundation frame and at its outer extremity is double-cranked at right angles to provide 45 a slide *u* which is engageable with an incline *v* on the spring blade *q*, this incline *v* being conveniently provided by slightly bending the outer intermediate part of the blade *q* into obtuse angular formation, and the terminal 50 slide part *u* of the connecting rod *t* being accommodated between this incline *v* and the adjacent face of the foundation frame *a*.

This controlling hand lever *s* is preferably of double-ended form as illustrated, pivoted 55 at an intermediate point *w*, with an oppositely directed pair of the connecting rods *t* jointed to its opposite ends, the lever *s* being thereby adapted for simultaneous releasing control of a pair of locking devices operating 60 respectively at opposite ends of the sectional frame *e*.

It will be seen that the present invention provides a means whereby each individual sectional tuft-yarn tube and spool carrier frame *e* may be detachably but rigidly locked 65

to the foundation case or frame *a*, independently of the adjacent sectional frame or frames, and without the necessity for the end plates *f* of adjacent sectional frames *e* being in actual contact. It will further be appreciated that these end plates *f* may be replaced if desired by bearing plates, either two or more in number, located in any convenient positions longitudinally of the sectional frame *e*. 70

What I claim as my invention and desire to 75 secure by Letters Patent is:—

1. A tuft-yarn spool and tube carrier device, for use in looms for weaving carpets and like tufted pile fabrics, comprising a foundation frame of the full width required adapted to be supported at its ends, a plurality of sectional frames adapted for attachment to said foundation frame and placed end to end thereon so as to extend completely across the fabric, tubes joined together side by side upon each sectional frame, bearings on each sectional frame for the removable mounting of a separate spool, bearing plates on each sectional frame adapted for locating engagement with said foundation frame, and locking devices provided on said foundation frame for rigidly securing the sectional frames in position thereon. 80

2. A tuft-yarn spool and tube carrier device, for use in looms for weaving carpets and like tufted pile fabrics, comprising a foundation frame of the full width required adapted to be supported at its ends, a plurality of sectional frames adapted for attachment to said foundation frame and placed end to end thereon so as to extend completely across the fabric, tubes joined together side by side upon each sectional frame, bearings on each sectional frame for the removable mounting of a separate spool, bearing plates on each sectional frame adapted for locating engagement with said foundation frame, coengaging spacing studs on the bearing plates of adjacent sectional frames, fixed spacing and locating plates on said foundation frame adapted for engagement with said bearing plates, and locking devices provided on said foundation frame for rigidly securing the sectional frames in position thereon. 90

3. A tuft-yarn spool and tube carrier device, for use in looms for weaving carpets and like tufted pile fabrics, comprising a foundation frame of the full width required adapted to be supported at its ends, a plurality of sectional frames adapted for attachment to said foundation frame and placed end to end thereon so as to extend completely across the fabric, tubes joined together side by side upon each sectional frame, bearings on each sectional frame for the removable mounting of a separate spool, bearing plates on each sectional frame adapted for locating engagement with said foundation frame, a notch in each said bearing plate, and locking devices 100

provided on said foundation frame for rigidly securing the sectional frames in position thereon, said locking devices comprising a detent and a pressure spring therefor, the spring-pressed detent being adapted to cooperate with said notch so as to press the respective bearing plate into close engagement with said foundation frame.

4. A tuft-yarn spool and tube carrier device, for use in looms for weaving carpets and like tufted pile fabrics, comprising a foundation frame of the full width required adapted to be supported at its ends, a plurality of sectional frames adapted for attachment to said foundation frame and placed end to end thereon so as to extend completely across the fabric, tubes joined together side by side upon each sectional frame, bearings on each sectional frame for the removable mounting of a separate spool, bearing plates on each sectional frame adapted for locating engagement with said foundation frame, a notch in each said bearing plate, and locking devices provided on said foundation frame for rigidly securing the sectional frames in position thereon, said locking devices comprising a flexible spring blade secured to said foundation frame, a detent provided on said blade, an operating member, and intermediate mechanism connecting said operating member and said blade, the spring-pressed detent being adapted to cooperate with said notch under control of said operating member so as to press the respective bearing plate into close engagement with said foundation frame.

5. A tuft-yarn spool and tube carrier device, for use in looms for weaving carpets and like tufted pile fabrics, comprising a foundation frame of the full width required adapted to be supported at its ends, a plurality of sectional frames adapted for attachment to said foundation frame and placed end to end thereon so as to extend completely across the fabric, tubes joined together side by side upon each sectional frame, bearings on each sectional frame for the removable mounting of a separate spool, bearing plates on each sectional frame adapted for locating engagement with said foundation frame, locking devices provided on said foundation frame, adjacent each end of each sectional frame, for rigidly securing said sectional frame in position thereon, an operating member mounted on said foundation frame, and intermediate mechanism connecting said operating member and said locking devices, said operating member being adapted for simultaneous control of the pair of locking devices located adjacent opposite ends of the sectional frame.

60 In witness whereof I have hereunto set my hand.

ERNEST JOSEPH PERRY.
